UNITED STATES PATENT OFFICE.

JAMES WILLIAM BURNETT, OF HUNTINGTON, WEST VIRGINIA.

DESIGN FOR A KITCHEN-CABINET.

SPECIFICATION forming part of Design No. 26,184, dated October 13, 1896.

Application filed September 3, 1896. Serial No. 604,801. Term of patent 14 years.

To all whom it may concern:

Be it known that I, JAMES WILLIAM BURNETT, a citizen of the United States of America, residing at Huntington, in the county of Cabell and State of West Virginia, have invented and produced a new and original Design for Kitchen-Cabinets; and I do hereby declare the following to be a full, clear, and exact description of the same, reference being had to the accompanying drawing, forming a part thereof.

The accompanying drawing is a perspective view of a kitchen-cabinet made in accordance with my design.

15 The cabinet is mounted on legs or supports *a a*, the side edges of which are outwardly at their upper ends and inward at their lower ends, the curved portion being connected by a straight portion, as shown. The lower part 20 of the cabinet proper is made up of plain boards, and the forward ends of the side pieces are provided with reedings *b*. The front of said side pieces of the cabinet is provided with two panels *c c*, the edges of which present 25 moldings, as shown.

The front of the cabinet has a panel *d*, and on each side of this panel are drawers *e e*, the front boards of which are provided with vertical and transverse reedings. Above the drawers *e* and panel *d* said front is provided 30 with vertical and transverse reedings *g* and *g'*, between which is a panel *f*.

It will be noted that the front of the cabinet does not extend as high as the sides, and consequently the swinging top has an apron *h*. 35 This swinging top and part to which it is hinged are provided with moldings *i*.

The general configuration and ornamentation of the cabinet are as shown in the accompanying drawing.

Having thus described my improved design, 40 I claim—

The design for kitchen - cabinets herein shown and described.

In testimony whereof I affix my signature 45 in presence of two witnesses.

JAMES WILLIAM BURNETT.
